UNITED STATES PATENT OFFICE.

HANS RUDOLF LUTZ-RUSSELL, OF ZURICH, SWITZERLAND.

APPARATUS TO DEADEN THE NOISE OF TYPEWRITERS.

Application filed October 21, 1924. Serial No. 744,945.

To all whom it may concern:

Be it known that I, HANS RUDOLF LUTZ-RUSSELL, a citizen of Switzerland, residing at Zurich, 41 Göthardstrasse, Switzerland, in the Canton of Zurich and Republic of Switzerland, have invented a new and useful Apparatus to Deaden the Noise of Type-writers, of which the following is a specification.

10 This invention relates to an improved platen for typewriting machines, and its general object is to provide a platen which will reduce to a minimum the noise caused by the impacting type during the operation thereof.

Another object is to provide a combined platen and feed-roll having the above characteristics which may be readily introduced into service in existing machines, without the necessity for any alterations in the latter, said platen serving to receive and hold the paper and to feed the latter in the usual manner, and having means whereby the cushioning effect of the platen may be increased or decreased from the exterior without dismantling the machine or the platen.

A full and complete understanding of the invention may be obtained from a consideration of the following detailed description, taken in connection with the accompanying drawing forming a part of this specification; it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

45 Figure 1 is a longitudinal sectional view of the improved platen.

Figure 2 is a perspective view of a portion of a typewriting machine and showing the improved platen thereon.

50 The combined feed-roll and platen for typewriting machines, in the improved form, as herein shown and described, comprises a hollow cylinder 1 formed of semi-hard rubber, and having relatively thick walls so as to give the proper amount of resiliency and yet retain the true cylindrical shape, and to retain its axial alinement in the typewriting

machine for the proper functioning of the parts.

The cylinder 1 is of the same diameter and length as the existing platens in such machines and is adapted to receive and support the sheet or sheets of paper in the same manner and to feed the same either by means of the usual ratchet and pawl arrangement or by means of the customary hand wheels 65 generally used for the purpose.

The open ends of the cylinder 1 are each interiorly threaded for the co-acting threads of end heads 2 and 2' respectively, which are formed of suitable metal and are provided 70 with integral, outstanding trunnions 3 and 3', centrally located and axially alined with the longitudinal axis of the cylinder. The inner faces of the heads are of concavo-convex formation to snugly receive the ends of 75 an inner tube or bag 4 of elongated tubular form and made of soft, flexible rubber or other inflatable material, the ends 4' and 5 being of hemi-spherical form to fit the said end heads, and thus will be supported at all 80 points on its exterior surface by the cylinder and the heads.

The trunnion 3 is provided with a longitudinal bore or passageway 3'' communicating with the interior of the cylinder 1 85 and extending to the outer end thereof, said bore being adapted to receive a valve-stem 5', having suitable air-tight connection with the adjacent end 5 of the flexible, inflatable tube or bag 4, and adapted to conduct air 90 to the same when inflating the latter.

The outer end of the valve stem 5' extends beyond the end of the supporting trunnion 3, and is suitably threaded for the reception of the closure cap 6 which, in addition to the action of the valve proper, serves to prevent escape of air from the inner tube or bag. The trunnions 3 and 3' are equipped with the usual hand wheels 7 for turning the platen backwardly or forwardly to adjust the paper, in addition to the aforesaid pawl and ratchet means (not shown).

By removing the cap 6, an ordinary pump 7', indicated in dotted lines, may be applied to the extended end of the valve stem, and the required amount of air may be forced into the inner tube 4 which will expand sufficiently to reinforce the walls of the platen cylinder, and resist the force of the impacting type-bars 8, as the machine is 105 operated, and the cushioning effect thus produced, both by reason of the fact that the

cylinder is formed of semi-hard rubber and by reason of the inclosed tube or bag of compressed air, serves to deaden the sound of such impact, providing means for rendering the typewriting machine as nearly noiseless as it is possible to make the same.

From the foregoing it will be seen that a simple and cheaply-manufactured platen has been provided for use in typewriting machines, which may be installed for use in the same manner as the existing platens, without any alteration in the machine, and that the sheets of paper are handled in the same manner, with the added advantage that the noise of the hammering type-bars is almost entirely eliminated.

What is claimed is:

1. A platen for typewriting machines, comprising a cylindrical roller formed of semi-resilient material, removable heads secured in each end thereof and provided with trunnions for application to a typewriting machine, and inflatable means confined within the cylinder and adapted to bear against all points on the inner wall thereof to eliminate the noise of impacting type bars.

2. A substantially noiseless platen for typewriting machines, comprising a cylindrical roller formed of semi-hard rubber, removable metallic heads adapted to be screwed into each end of the cylinder, said heads each having a longitudinally-aligned

integral trunnion for application to the said machine, one of said trunnions having a longitudinal bore, an inner bag fitting within the cylinder and having a valve stem to traverse the bore in the stem for inflating the inner bag to support the walls of the platen at all points and lessen the noise of impacting type-bars.

3. Means for reducing the noise of typewriting machines, comprising a combined platen and feed-roll formed of a semi-hard rubber cylinder and having relatively thick walls, removable metallic heads secured in each end of the cylinder, each head having an axially-aligned trunnion to constitute bearings for the cylinder and having hand wheels to turn the same, one of said trunnions being provided with a central, longitudinal bore, a flexible, air-tight expansible bag fitting the space within the cylinder and between the heads, a valve stem communicating with one end of the expansible bag and extending through the bore in said trunnion to permit inflation of the bag and to cushion the walls of the cylinder, against the impact of type-bars of the said machine, and a closure cap fitting the valve stem at the end of the trunnion to prevent escape of air.

In testimony that I claim the foregoing as my own, I have hereto affixed my signature.

HANS RUDOLF LUTZ-RUSSELL.
